UNITED STATES PATENT OFFICE.

FRANK A. BEAL, OF HAVERHILL, MASSACHUSETTS.

TURNED SHOE.

1,097,511.

Specification of Letters Patent.

Patented May 19, 1914.

Application filed June 16, 1913. Serial No. 773,848.

To all whom it may concern:

Be it known that I, FRANK A. BEAL, a citizen of the United States, residing at Haverhill, county of Essex, State of Massachusetts, have invented an Improvement in Turned Shoes, of which the following description, in connection with the accompanying drawing, is a specification, like characters on the drawing representing like parts.

10 This invention relates to shoes and particularly to so-called "turned shoes" and so-called "McKay" shoes and the object of the invention is to provide a novel construction which permits a turned or McKay shoe 15 to be readily tapped when the sole becomes worn. I secure this object by splitting the sole of the shoe to make a wear portion on the bottom of the sole and an upper portion which is separate from the wear portion at 20 the edges of the sole and to which the upper is secured by stitches which extend through the upper portion only. With such a construction the wearing away of the wear portion of the sole does not affect the stitches 25 which hold the upper to the sole and when such wear portion has been completely worn away the shoe may still be tapped by simply sewing a fresh sole or tap to the upper portion of the sole.

30 Although my invention is applicable to turned shoes it is equally applicable to so-called McKay shoes. I have chosen herein to illustrate it as it would be applied to turned shoes such as shown in my former 35 Patents Nos. 887,456 dated May 12, 1908 and 899,501 dated Sept. 29, 1908. The shoe illustrated in said patents is what I have termed a "turned welt" shoe and it comprises a sole having a welt sewed thereto and 40 an upper which is sewed to the welt, said upper being sewed to the welt in the first instance wrong side out, after which the shoe is turned as is usual in turned shoes. A shoe made in accordance with said patents 45 has all the appearance and many of the advantages of a welt shoe but at the same time it has the flexible quality of a turned shoe.

In order to give a proper understanding of the invention I have illustrated some selected embodiments thereof which will now be described it being understood that the invention is not confined to the illustrated forms thereof.

50 In the drawings Figure 1 shows a shoe partly in section made in accordance with my invention. Figs. 2, 3 and 4 represent different steps in the process in making the

shoe. Fig. 5 is a cross sectional view showing the upper sewed to the sole before the shoe is turned. Fig. 6 is a view similar to Fig. 5 showing the shoe turned and the two portions of the sole fastened together. Fig. 7 is a view similar to Fig. 5 showing a different form of the invention.

In making a turned welt shoe in accordance with my invention I provide a sole 1 and then split the sole at the edges so as to form the welt-supporting portion 2 and the wear portion 3. The sole may simply be split in from the edges a short distance as shown in Fig. 7, or it may be split from one side to the other as shown in Figs. 4, 5 and 6. In either case this operation of splitting the sole forms at the edge thereof a welt-supporting portion 2 on the top of the sole 75 and a wear portion 3 on the bottom of the sole. After the sole is thus split, the welt-supporting and wear portions 2 and 3 are separated and a welt 4 is applied to the top of the welt-supporting portion 2 and is 80 sewed thereto by means of stitches 5. These stitches extend only through the welt-supporting portion. After the welt has thus been sewed to the sole, the upper 6 is stitched to the welt wrong side out as is commonly 85 done in turned shoes and as shown in Fig. 5, said upper being sewed to the welt by stitches 7. These stitches 7 may either cross or interlock with the stitches 5 that secure the welt to the sole or they may be free from 90 the stitches 5 as desired. After the upper has thus been sewed to the welt, the shoe is turned right side out as shown in Fig. 6, after which the two portions of the sole are 95 united at the edge by stitches 8 which are shown as extending through both portions of the sole and through the welt as well. These stitches 8 will preferably be of the lock-stitch type such as is used in the manufacture of so-called "welt" shoes. The 100 split edge of the sole 1, the welt and the stitches 8 which unite the two portions of the sole together and extend through the welt, give the shoe in all essential particulars the appearance of a welt shoe but at 105 the same time the shoe is a turned shoe and has the desirable flexible qualities of a turned shoe. The advantage of splitting the sole to form the separate welt-supporting and wear portions at the edge of the sole 110 is that the stitches 5 which unite the welt to the sole do not extend through the bottom of the sole and therefore are not affected by the wearing away of the wear portion 3 of

the sole. In making the shoe, I prefer to extend the slit at the edge back to about the shank of the shoe where the welt ordinarily terminates, but my invention is not limited 5 to any particular length of slit.

Where the above construction is used the shoe may be worn until the wear portion 3 of the sole is entirely worn away before the stitches 5 are at all affected. When the shoe 10 is worn to this point it may be readily tapped or resoled by simply cutting the wear portion 3 from the sole at the rear end of the split as shown at 10 and then sewing a tap or new sole to the shoe by stitches 15 which extend through the welt and welt-supporting portion of the sole in exactly the same way as would be done in tapping a welt shoe. It will thus be seen that my improved shoe has all the advantages of a welt 20 shoe so far as durability and facility of repair are concerned and yet it has all the advantages which a turned shoe has in addition.

In order to strengthen the stitches which 25 unite the upper 6 to the welt 4 I will preferably provide the sole 1 with a reinforcing lip 11 which overlies the inner face 12 of the welt and through which pass the stitches 7 that unite the upper to the welt. This reinforcing lip 11 can be formed by channeling the upper side of the sole slightly and then turning up the channel portion to form the lip, or it may be formed in any other suitable way. I will also preferably provide 30 the top of the welt 4 with a groove 13 at the point where the stitches 7 extend through the upper side of the welt. Where this construction is employed the stitches 7 will draw the upper down into the groove 13 35 somewhat as shown in Fig. 5, thus making a superior construction. Furthermore, this groove 13 acts as a guide for properly placing the line of stitching 7.

The drawings show the preferred embodiments of my invention but I have not attempted to illustrate all possible ways in which the invention might be embodied and, therefore, do not wish to be limited to the 45 constructional features shown.

The invention can also be applied to a 50 turned shoe which does not have a welt incorporated therein and may be also embodied in a so-called McKay shoe, in both of which cases the stitches which unite the upper to the sole would pass through the 55 part of the sole corresponding to the welt-supporting portion 2 in the accompanying drawing but would not pass through the wear portion.

Having fully described my invention, what I claim as new and desire to secure by Letters Patent is:

1. A turned shoe comprising a sole which

is split at the edges to form a welt-supporting portion and a wear portion, and a welt 65 sewed to the sole by stitches which extend through the welt-supporting portion only, an upper stitched to the welt and means securing together the welt-supporting and wear portions of the sole. 70

2. A turned shoe comprising a sole having as integral parts thereof a wear portion and a welt-supporting portion which are separate from each other, a welt sewed to the sole by stitches which extend through the 75 welt supporting portion only, an upper stitched to the welt, and means extending through the welt and both portions of the sole for securing them together.

3. A turned shoe comprising a sole which 80 is split from one side to the other and from the front to at least the shank portion thereby to form a welt-supporting portion and a wear portion, a welt secured to the welt-supporting portion only, an upper stitched 85 to the welt and stitches extending through the welt and both portions of the sole at the edge thereof thereby uniting them together.

4. A turned shoe comprising a sole which 90 is split at the edges to form a welt-supporting portion and a wear portion, a welt sewed to the sole by stitches which extend through the welt-supporting portion only, said sole having a reinforcing lip which overlies the 95 inner edge of the welt, an upper secured to the welt by stitches which extend through the upper, the welt and reinforcing lip, and means connecting the welt-supporting and wear portions of the sole. 100

5. A turned shoe comprising a sole which is split at the edges to form a welt-supporting portion and a wear portion, a welt sewed to the sole by stitches which extend through the welt-supporting portion only, said welt 105 having a groove in the top thereof, an upper secured to the welt by stitches which extend therethrough along the line of the groove and means for uniting the two portions of the sole together at the edges. 110

6. A shoe comprising a sole which is split at the edges to form a wear portion and an upper portion, an upper, and means for securing said upper to the sole which includes 115 stitches which extend through said upper portion only of the sole but do not extend through the wear portion and stitches securing together the two portions of the sole adjacent the edge thereof.

In testimony whereof, I have signed my 120 name to this specification, in the presence of two subscribing witnesses.

FRANK A. BEAL.
